UNITED STATES PATENT OFFICE.

ELLSWORTH A. HAWTHORNE, OF BRIDGEPORT, CONNECTICUT.

DESIGN FOR A LAMP.

44,706.

Specification for Design.

Patented Sept. 30, 1913.

Application filed July 31, 1913. Serial No. 782,359. Term of patent 14 years.

To all whom it may concern:

Be it known that I, ELLSWORTH A. HAWTHORNE, a citizen of the United States, and a resident of Bridgeport, county of Fairfield, and State of Connecticut, (whose post-office address is 35 Spruce street, Bridgeport, Connecticut,) have invented a new, original, and ornamental Design for Lamps, of which the following description, in connection with the accompanying drawings, is a specification, like characters on the drawings representing like parts.

In the drawing, Figures 1 and 2 are a plan and side elevation, respectively, of a lamp showing my new design.

What I claim is:

The ornamental design for a lamp, as shown.

In testimony whereof, I have signed my name to this specification, in the presence of two subscribing witnesses.

ELLSWORTH A. HAWTHORNE.

Witnesses:

E. HORACE HAWTHORNE,
E. LOUISE SCOTT.
